HEADBOARD FOR BEDS

James E. Jones, Toledo, Ohio, assignor to The Hettrick Manufacturing Company, Toledo, Ohio, a corporation of Ohio

Application October 11, 1954, Serial No. 32,615

Term of patent 14 years

(Cl. D5—4)

FIG. 1

To all whom it may concern:

Be it known that I, James E. Jones, a citizen of the United States and a resident of Toledo, Lucas County, Ohio, have invented a new, original, and ornamental Design for a Headboard for Beds, of which the following is a specification, reference being had to the accompanying drawing forming a part thereof.

In the drawing:

I claim:

The ornamental design for a headboard for beds, as shown.
